SAMUEL E. SPERRY, OF HOLLIS, NEW YORK, ASSIGNOR TO INTERTYPE CORPORATION,
OF BROOKLYN, NEW YORK, A CORPORATION OF NEW YORK

ESCAPEMENT MEANS FOR TYPOGRAPHICAL MACHINES

Application filed May 31, 1930. Serial No. 458,427.

The present invention relates to improvements in typographical machines and more especially to those of the general class disclosed in U. S. Letters Patent No. 436,532 granted September 16, 1890 to O. Mergenthaler, wherein matrices which are assembled into lines for the casting of type bars or slugs therefrom are stored in magazines which are inclined forwardly and downwardly and the matrices are delivered from the lower forward ends of the magazines under the control of escapements which are actuated by a keyboard at the front of the machine.

Some machines of this class have been heretofore constructed to receive and use magazines carrying escapements for controlling the delivery of the matrices from the different channels thereof, such escapements on the magazines being brought into position to be actuated by the keyboard mechanism of the machine when such magazines are placed in operative position and preventing spilling of the matrices from the lower ends of the magazines when the latter are removed from operative position in the machine, and other machines of this class have been heretofore constructed to receive and use magazines which do not carry matrix controlling escapements but the matrix controlling escapements for such magazines were permanently mounted on the framework of the machine or on the frames on which the magazines are placed when mounting them in the machine, so that such escapements would cooperate with the magazines, when the latter are mounted in the machine, to control the delivery of matrices therefrom, but such escapements remain in the machine when the magazines are removed therefrom, the use of a matrix locking bar across the lower or matrix delivery end of such magazines being required to prevent spilling of matrices therefrom at all times except when the magazines were mounted in the machine.

Such machines have presented the objection that each of such types of machines was able to use only magazines of the particular type for which they were constructed, that is machines of the type constructed to use magazines carrying their own matrix con-

trolling escapements could not use magazines of the type not carrying escapements, and vice versa with the result that the range of usefulness of the machines and the magazines was restricted.

The primary object of the present invention is to provide means whereby a typographical machine of this class is adapted to receive matrix magazines either of the type carrying matrix controlling escapements or of the type not carrying such escapements and to effect the selective delivery of matrices from either type of magazine under control of the same escapement actuating means.

More particularly, the object of the invention is to provide means for adapting a typographical machine of this class to receive matrix magazines of the types either with or without their own escapements by detachably or removably applying escapement means to the machine to cooperate with magazines not equipped with their own escapements, so that such escapement means and the escapements of magazines equipped with their own escapements will cooperate with the same escapement actuating reeds in the machine, the escapement means for magazines not equipped with their own escapements being removable from the machine so that they will not obstruct the escapements of a magazine equipped with its own escapements when such a magazine is substituted therefor.

By enabling machines of this class to thus interchangeably receive and use magazines both of the type containing controlling escapements and those of the type not containing such escapements, the users of such machines are enabled to use all machines on hand of both types and thus utilize the full supply or assortment of matrix fonts available with substantially uniform facility.

To these and other ends, the invention consists in certain improvements and combinations and arrangements of parts all as will be hereinafter more fully described, the features of novelty being pointed out particularly in the claims at the end of the specification.

In the accompanying drawings:—

Fig. 1 is a side elevation of the upper portion of a typographical machine embodying the present invention;

Fig. 2 is a side elevation, on an enlarged scale, of the lower or matrix delivery ends of the matrix magazines as shown in Fig. 1, the lowermost magazine being of the type containing matrix controlling escapements and the two upper magazines being of the type not containing such escapements but co-operating with escapement means removably or detachably mounted in the machine;

Fig. 3 is a view similar to Fig. 2 but showing the magazines rocked into position for removal and the escapement means removed from operative relation with the upper magazines;

Fig. 4 is an enlarged view in perspective showing collectively one of the escapement carriers and a portion of the machine on which it is detachably mounted; and

Fig. 5 is a rear elevation of one end of the escapement carrier shown in Fig. 4.

Similar parts are designated by the same reference characters in the several figures.

The invention is shown in the accompanying drawings and will be hereinafter described in detail as applied to a machine of well known type in which a plurality of matrix magazines are arranged in a stack so that the ends thereof are in offset or staggered relation to one another and the stack is shiftable to bring any selected magazine into operative position with respect to the usual assembling and distributing mechanisms of the machine, but it is to be understood that the invention is applicable to other forms of typographical machines and that the invention is not restricted to the particular embodiment of the invention shown but may be carried out by the use of equivalent constructions and such are included within the scope of the claims.

In the embodiment of the invention shown, 1 represents the upper portion of the framework of a typographical machine of the general class shown and described in the patent hereinbefore mentioned, this framework supporting an assembler front 2 leading to suitable mechanism which assembles the matrices in lines preparatory to the casting of type bars or slugs therefrom, and 3 represents the distributing mechanism which returns the matrices to the magazine from which they were drawn, after the type bar or slug has been cast from the matrix line, the assembling and distributing mechanisms being, for example, similar to those commonly used in machines of this class so that further illustration and description thereof is unnecessary. Three matrix magazines, 4 and 5 are shown, each magazine embodying top and bottom plates grooved to receive matrices edgewise between them and

to contain a font of matrices, the magazines being mounted respectively on three similar frames 6 so that they form a stack and lie in a forwardly and downwardly inclined position so that the matrices delivered to their upper ends from the distributing mechanism will slide downwardly therein by gravity and the matrices in these magazines, when released, will descend by gravity from their lower ends and drop into the assembled front, in a well known manner. The magazine supporting frames are connected together in proper spaced relation by brackets 10 and 11 at the side edges thereof, the magazine frames being so related that the upper and lower ends of the magazines will be in offset or staggered relation to one another, as will be clear from Fig. 1. The magazine stack is arranged to shift forwardly and rearwardly in any desired way to bring any selected magazine therein into operative relation with the assembled front 2 and distributor mechanism 3, magazine shifting mechanism of this kind being well known in the art so that detailed illustration and description thereof is deemed unnecessary, although it may be noted that the magazine stack and the supporting frames therefor in the present instance are shown mounted on a carrier 12 which is supported at each side thereof to shift forwardly and rearwardly and to rock on a roller 13 arranged in fixed position on the frame of the machine the forward portion of the carrier having a track 7 thereon which rides on a roller 8 carried by a lever 9 which is pivoted at 9^a on the main frame, a second lever 90 being also pivotally mounted at 9^a and connected by a lever 91 to the magazine carrier, so that the magazine stack may occupy either a forwardly and downwardly inclined position with its track 7 resting on the roller 8 as shown by the full lines in Fig. 1, in which position the lower and upper ends of the magazines will be in operative relation with the assembler front and distributor mechanism, and one or another of the magazines in the stack may be brought into operative position by first lowering the lever 9, thereby raising the roller 8 and track 7 and the forward ends of the magazines so that they will be lifted above the escapement actuators, then swinging the lever 90, thereby shifting the magazine stack forwardly or rearwardly as required to bring the desired magazine into proper position, and then raising the lever 9 and thereby lowering the selected magazine into operative position, or the magazine stack may be rocked into a rearwardly and downwardly inclined position about the centers of the rollers 13 as an axis, as shown by the dotted lines in Fig. 1, in which position the magazines will be accessible for removal from their supporting frames, substantially as shown and described in U. S. Letters Patent No. 1,731,154

granted October 8, 1929, to S. E. Sperry, the magazines being slidable endwise on their respective frames so that they may be inserted and removed from the rear ends thereof. The escapement actuators which operate the escapements controlling the delivery of the matrices from the magazines, may be of any desired form, they being indicated in the present instance as consisting of vertically movable rods or reeds 14 such as those commonly used in machines of this class, the upper ends of these rods being guided in the upper portion of the main stationary frame to reciprocate vertically and the lower ends of these rods cooperate with the usual keyboard mechanism of the machine.

In the instance shown, the two upper magazines 4 of the stack are of the type having no matrix controlling escapements built thereon, these magazines being provided with any suitable or known form of matrix locking bars 15, those shown being slidable across the lower or matrix delivery ends of these magazines so that when in position they will lie between the lugs on the upper edges of the lowermost matrices M in the respective magazines and thereby prevent spilling of these matrices and the rest of the matrices resting thereon from these magazines when the latter are removed from operative position in the machine or are not in use, these locking bars being shown in place in Fig. 3 wherein the magazines are shown shifted out of operative position in the machine and the separate escapements for these magazines are in detached relation thereto.

Simplified escapement means for magazines of the type having no escapements contained thereon is shown in the present instance as comprising a solid bar 16 which is formed at its upper side with surfaces on which are mounted a pair of rails 17 having channels 18 cut therein and spaced to correspond with the spacing of the usual matrix guiding channels or grooves in the bottom plate of the magazine, the rails 17 being adapted to enter slots 19 which extend across the bottom plate of the magazine 4 adjacent to the lower or matrix delivery end thereof. The portion of the bar 16 beneath the rails 17 is provided with a series of slots 20 corresponding in width and spacing to the width and location of the channels 18 in the rails 17, and an escapement or verge 21 is contained in each of these slots in the bar 16, the escapements being of arcuate form, and a correspondingly arcuate or transversely curved cap or cover plate 22 is secured at its ends to the bar 16 and overlies the series of escapements and provides a bearing on which the escapements rock. The ends of each arcuate escapement form pawls which are movable alternately into the channels 18 of the bars 17 by the rocking movement of the escapement. Each escapement is provided

with a spring 23 having one end bent or formed to bear on a lug 21° on the respective escapement to hold it in normal position as shown in Fig. 4 and to return it to such position after each actuation thereof, these springs entering the slots 20 and being secured to the bar 16 by fitting their ends tightly into holes 24 which are formed in a row or series along the under side of the bar 16, each spring being preferably composed of spring wire and having a resilient coil 23^a formed therein between its ends. The series of escapements are retained in the respective slots in the bar 16 by a wire pin 25 which extends through the slotted portion of the bar 16. These escapements cooperate with the matrices in the magazine to control the delivery of the matrices therefrom substantially in the manner described in U. S. Letters Patent No. 1,153,078 granted September 7, 1915 to T. S. Homans, it being clear from Fig. 2 that when the escapement is in its normal position the lower pawl thereon will engage the lowermost matrix in the magazine to prevent its delivery therefrom but when the pawl is rocked into a reverse position against the action of the spring 23, the lower pawl of the escapement will be lowered out of engagement with the lowermost matrix, thus permitting its delivery from the magazine while at the same time the upper pawl on the escapement will be raised to catch and hold the next following matrix, and upon the return of the escapement to normal position, the upper pawl thereon will be lowered out of engagement with the matrix which it engages and the lower pawl on the escapement will be raised to catch such matrix, it being assumed that the magazine is then in operative position in the machine and the locking bar 15 is withdrawn.

Means is provided for detachably mounting the escapement means on any of the magazine supporting frames of the machine so that when mounted on such frame it will be in operative relation with a magazine thereon of the type not provided with its own escapements and with the usual escapement actuating reeds in the machine. In the construction shown, a pair of arms 26 are fixed to the ends of the escapement carrying bar 16, the inner corners at the ends of these arms being formed with bevelled surfaces 27 and the arms being provided at their inner sides with holes or recesses 28, and each of the magazine supporting frames 6 is provided at its opposite sides with spring-pressed plungers or detents 29 which project outwardly or laterally from surfaces 30 at the outer sides of these frames, these surfaces bearing against the inner sides of the arms 26 and thereby accurately positioning the escapement carrying bar 16 in a direction transversely of a magazine on the frame 6 when the escapement means is ap-

plied to such frame, and the spring-pressed plungers 29 in said frame engaging in the holes or recesses 28 in the arms 26 and thereby holding the escapement means on the magazine frame. Preferably, means is provided for holding the escapement means in operative and inoperative positions with respect to a magazine on the respective frame 6, this being accomplished in the present instance by providing spring-pressed detents 31 which project outwardly from the respective surfaces 30 on the frame 6 and are adapted to engage in either of two vertically spaced holes or recesses 32 in the inner sides of the respective arms 26 of the escapement means, the engagement of the detent 31 in the lower hole 32 holding the escapement means in its upper position and in cooperative relation with the magazine on the respective frame as shown in Fig. 2 and the engagement of this detent with the upper hole 32 holding the escapement means in a disengaged position relatively to the magazine as shown in Fig. 3. By rounding the outer or exposed ends of the detents 29 as shown, these detents will ride upon the bevelled surfaces 27 on the arms 26 and will be thereby forced inwardly while the escapement means is being applied to the frame 6, then spring outwardly into the holes or recesses 28 when the escapement means reaches its proper position and the escapement means may be detached from the frame 6 by applying a pulling force thereto, the rounded outer ends of the detents 29 causing them to be pushed inwardly and disengaged from the holes or recesses 28, and by similarly rounding the outer or exposed ends of the detents 31, they will be automatically disengaged from one or the other of the holes or recesses 32 when sufficient vertical force is applied to the escapement means to swing it into operative or inoperative position about the detents 29 acting as pivots. It will be understood that prior to swinging the escapement means from the upper operative position shown in Fig. 2 to the lower or inoperative position shown in Fig. 3, the locking bar 15 is inserted in the magazine to lock the matrices against spilling from the lower or matrix delivery end thereof, since the escapement means when swung into the inoperative position shown in Fig. 3, no longer controls the matrices in the respective magazines. In order to remove either of the magazines 4 when desired, it is only necessary to insert the locking bar and then depress the escapement means by pushing downwardly on its forward end so that it is brought into the position shown in Fig. 3, it being then disengaged from the magazine and the latter may be removed by sliding it rearwardly on its frame, as indicated by the arrow in said figure.

65 The lowermost magazine 5 of the stack is

of the type which contains matrix controlling escapements, this magazine being shown provided with escapements 21^a which remain attached to or form a part of the magazine, they being like the escapements shown in the Homans Patent No. 1,153,078 hereinbefore referred to, and magazines of this type do not require the application of an escapement attachment or a locking bar thereto. Accordingly, in Figs. 1, 2 and 3, escapement attachments are applied to the magazine frames which support the two uppermost magazines 4 but no escapement attachment is applied to the frame supporting the lowermost magazine 5 although the frame supporting this magazine is preferably provided with the detents 29 and 31 so that it may receive an escapement attachment when a magazine of the type not carrying escapements is mounted on this frame.

In practice, the machine may be constructed substantially as shown in Figs. 1 to 3 inclusive, the magazine supporting frames 6 being all provided with the detents 29 and 31 toward their forward ends and these frames may all receive magazines of the type carrying their own escapements, like the lowermost magazine 5 or magazines not provided with such escapements but using a locking bar, like the two uppermost magazines 4, or magazines of both types may be mounted on the different frames. In order to enable magazines of the type not provided with escapements to be used in a machine constructed to use magazines carrying their own escapements or to be used in a machine containing one or more magazines carrying their own escapements, it is only necessary to apply the escapement means to the magazine supporting frames 6 on which the magazines not containing escapements are mounted, the detents 29 and 31 removably holding the escapement means on such frames and when the escapement means are swung upwardly into operative position and the locking bar or bars 15 are withdrawn from the respective magazines, such escapement means will control the delivery of matrices from the respective magazines. Preferably, the operating portions 21^b and 21^c of the escapements, with which the escapement actuators 14 cooperate, are alined or similarly located with respect to the different magazines so that shifting of the magazines in a forward or rearward direction to bring one or another of the magazines into operative relation with the assembler front 2 and the distributor mechanism 3 will also bring the escapements of the selected magazine into proper working relation with the escapement actuators 14, so that operation of the escapement actuators, under the control of the usual keyboard, will cause actuation of the escapements of the magazine in operative position and will cause delivery of matrices therefrom to the

- assembler front. The escapement attachments, when applied to the supporting frames for the magazines not carrying their own escapements do not interfere with the shifting movements of the magazine stack to bring any selected magazine therein into operative position, they receiving the escapement actuators 14 between the arms 26 and in rear of the bar 16. Removal of any magazine not provided with its own escapements may be effected quickly after the locking bar 15 has been applied thereto and the respective escapement means has been swung downwardly into inoperative position and if such magazine is replaced by one carrying its own escapements, like the lowermost magazine 5, the escapement means may quickly be detached from the magazine frame receiving such a magazine, it being understood that the escapement means is applied to a magazine frame whenever a magazine not provided with its own escapements is mounted on such frame.
- The present invention provides simplified and improved means to enable the same machine to receive and use magazines either of the type provided with their own matrix controlling escapements or those of the type not provided with their own escapements, the machine being operative interchangeably with either or both types of magazines and enabling the user to utilize with equal facility all matrix fonts on hand, whether they are contained in either or both types of magazines, without requiring any change in the escapement actuators, the escapements in the attachments for magazines not equipped with their own escapements and the escapements in the magazines equipped with their own escapements cooperating in the same manner with the set of escapement actuators already in the machine.
- I claim as my invention:
1. In a typographical machine having a set of escapement actuators, means for interchangeably supporting a matrix magazine equipped with matrix controlling escapements to cooperate with the escapement actuators and a magazine not equipped with such escapements, and removable escapement means to cooperate with the magazine not equipped with escapements and with the escapement actuators, whereby said actuators may control the delivery of matrices from either of such magazines.
  2. In a typographical machine having a set of escapement actuators, means for supporting a magazine stack including a plurality of frames to receive the respective magazines, and escapement-carrying attachments having means for removably connecting them to said magazine receiving frames and supporting them independently of magazines thereon in cooperative relation therewith.
  3. In a typographical machine having a set of escapement actuators, means for supporting a stack of matrix magazines therein, and escapement-carrying attachments having means independent of the magazines for interchangeably mounting said attachments in the machine in operative relation with the different magazines in the stack.
  4. In a typographical machine having a set of escapement actuators, means for supporting a plurality of matrix magazines, and an escapement carrier removably mounted on one or another of said magazine supporting means to cooperate with the escapement actuators and the magazine thereon to control the delivery of matrices therefrom, said carrier being supported independently of the magazines and movable on the respective magazine supporting means to and from operative relation with the magazine thereon.
  5. In a typographical machine having a set of escapement actuators, means for supporting a stack of matrix magazines including a plurality of frames to receive the respective magazines, and escapement carrying attachments to cooperate with the escapement actuators and the magazines, said magazine receiving frames having means for removably attaching the attachments thereto.
  6. In a typographical machine having a set of escapement actuators, frames for supporting matrix magazines, and escapement carrying attachments to cooperate with the escapement actuators and magazines on said frames, said frames having spring-pressed plungers thereon and the escapement attachments having recesses to detachably receive said plungers to detachably connect said attachments to said frames.
  7. In a typographical machine having a set of escapement actuators, frames for supporting matrix magazines, and escapement carrying attachments to cooperate with the escapement actuators and magazines on said frames, said frames having spring-pressed plungers thereon and each of said attachments having recesses therein to cooperate with said plungers and thereby hold the escapement carrying attachment in operative and inoperative relationships with the respective magazine.
  8. In a typographical machine having a set of escapement actuators, a plurality of magazines movable bodily to bring one or another into operative relation therewith and comprising magazines equipped with matrix escapements and magazines not equipped with such escapements, and removable escapement means to co-operate with the latter magazines and with the escapement actuators.
  9. In a typographical machine having a set of escapement actuators, magazine supporting frames carrying a plurality of magazines shiftable as a whole to bring one or another magazine into operative position, the supporting frame for each magazine be-

ing capable of receiving magazines with escapements and magazines not having escapements, and escapement means detachably associated with the magazines not having escapements and with the escapement actuators, said means when in active position being free to move with the magazines and their supporting frames to clear the escapement actuators.

10. Matrix controlling escapement means for matrix magazines not equipped with escapements and having slots extending across the bottom thereof, comprising a bar having slotted rails on its upper side to removably enter the slots in the bottom of the magazine, said bar having transverse slots therein beneath said rails, single escapement pawls movably mounted in the respective slots, and controlling springs for the escapements extending into said slots.

In testimony whereof I have hereunto set my hand.

SAMUEL E. SPERRY.
